UNITED STATES PATENT OFFICE.

CEPHAS V. FITE AND CHARLES C. CODDINGTON, OF CHARLOTTE, NORTH CAROLINA.

INTERNAL-COMBUSTION ENGINE.

1,339,187.

Specification of Letters Patent.

Patented May 4, 1920.

Application filed January 30, 1919. Serial No. 274,015.

To all whom it may concern:

Be it known that we, CEPHAS V. FITE and CHARLES C. CODDINGTON, citizens of the United States, residing at Charlotte, in the 5 county of Mecklenburg and State of North Carolina, have invented new and useful Improvements in Internal-Combustion Engines, of which the following is a specification.

10 This invention relates to four-cycle internal combustion engines, and one object of the same is to utilize the explosive force of the fuel or fuel mixture to the best power generating advantage by the employment 15 in each cylinder unit of two working pistons having differentiating timed operations in regular order and receiving the fuel or mixture between them under compression and subjecting it to additional compression previous to ignition.

A further object of the invention is to eliminate cylinder valves and, in fact, all valves as much as possible in connection with the cylinder of an internal combustion engine and to rely upon two working pistons not only to effect a preliminary and subsequent compression of the fuel or fuel mixture but to control the admission of the fuel or fuel mixture between the pistons 25 under partial compression for the purpose of additional compression thereof prior to ignition and finally to expedite the exhaust of the spent gases and a thorough scavenging of each cylinder unit.

30 A still further object of the invention is to reduce the usual equipment or accessories of each cylinder unit to a minimum and thereby materially reduce the cost of manufacture and also avoid the wear of parts and 35 the necessary repair and replacement thereof with advantages in the positive action of the engine as a power generating medium and wherein the parts are compactly arranged and are of comparatively simplified 40 construction.

45 With these and other objects and advantages in view, the invention consists in the preferred construction and arrangement of the several parts which will be more fully 50 hereinafter described and claimed.

In the drawings:

Figure 1 is a transverse vertical section through one of the cylinder units of the improved internal combustion engine show-

ing the pistons at the beginning of the 55 power stroke.

Fig. 2 is a similar view illustrating the 60 pistons and coöperating mechanism at the end of the power stroke or beginning of the exhaust.

Fig. 3 is a similar view showing the pistons operating to clear the cylinder of the burnt gases.

Fig. 4 is a similar view illustrating the 65 beginning of the in-take stroke when a vacuum will be formed between the two working pistons and the mixture compressed by the compression element of one of the pistons.

Fig. 5 is a similar view showing the 70 pistons arranged in position to receive the explosive charge to subject the same to further compression and ignition and also illustrating the completion of one power stroke 75 relatively to the pistons and coöperating parts shown by Fig. 1.

Fig. 6 is a horizontal section taken in the plane of the line 6—6, Fig. 1.

Figs. 7, 8, 9, 10 and 11 are views, respectively, similar to Figs. 1, 2, 3, 4 and 5, and 80 illustrating the use of a sleeve valve motion in addition to the two working pistons and other parts embodying the features of the invention.

Fig. 12 is a horizontal section taken in the 85 plane of the line 12—12, Fig. 7.

The numeral 5 designates a main combustion cylinder having thereon a compression cylinder 6, the cylinder 5 opening at its lower extremity into a crank case 7 and the 90 compression cylinder 6 having a top dome or cap 8 for closing the same. The cylinders 5 will be grouped in varying multiples as in the usual internal combustion engine structures and extending into and through 95 the crank case 7 common thereto as a crank or power shaft 9 and similarly extending through the dome or cap 8 is an upper auxiliary crank shaft 10, these crank shafts, respectively, having cranks 11 and 12 exposed within the crank case and dome or cap. Within each cylinder two working pistons 13 and 14 are mounted and preferably formed hollow with their inner closed working faces 15 and 16 in opposition, the 100 outer ends 17 of the pistons being open for convenience of operative association therewith of connecting rods 18 and 19, respec-

105

tively, attached to the cranks 11 and 12 of the shafts 9 and 10. Each cylinder has an in-take pipe 20 which is attached or applied to the lower portion of the compression cylinder 6 and opens into the latter, the said pipe being provided with an inwardly opening check valve 21. At an intermediate point each cylinder is provided with an exhaust port 22 opening into an exhaust pipe 23, and in addition the cylinder is provided with the usual water jacket 24 which will be readily understood. At a suitable distance below the exhaust port 22 a sparking plug 25 is exposed to the interior of the cylinder, said plug being so positioned relatively to the strokes of the working pistons that ignition will be effected at the time when the lower working piston 13 is at the upper limit of its stroke within the cylinder. The upper part of the cylinder at one side is formed with a by-pass 26 opening into the lower portion of the compression cylinder 6 and communicating therewith is an in-take port 27 which extends vertically or is elongated and intersects and fully communicates with a lower port 28 opening into the combustion chamber 5^a defined by the cylinder and in which the pistons have reciprocation. The by-pass 26 is formed by recessing or diametrically diminishing the upper portion of the wall of the upper working cylinder 14, as at 29, the two pistons 13 and 14 closing and opening the exhaust port 22 and ports 27 and 28 at regular intervals during the cycles or the completion of one power stroke of the pistons. In the form of the internal combustion engine as shown by Figs. 1 to 6, inclusive, the working pistons 13 and 14 directly bear against the inner surface of the wall of the combustion chamber 5^a and will be provided with suitable packings or packing rings to obstruct leakage and on the upper end of the upper piston 14 is a compression piston 30 which extends over or projects laterally relatively to the upper end of the said piston and engages the wall of the compression cylinder 6 and works evenly or regularly with the said upper piston to which it is fixed. The compression piston 30 also controls the open and closed position of the in-take pipe 20 relatively to said compression cylinder and thereby regulates the inlet of the fuel or fuel mixture into the compression cylinder and the main combustion cylinder. The compression of the charge of fuel or fuel mixture below the compression piston 30 is effected against the upper exposed portion 31 of the end of the cylinder 5 located within the compression cylinder 6 and also downwardly through the by-pass 26 and port 27, this compression of the fuel or fuel mixture being effected by the compression piston when the port 28 to the combustion chamber is closed by the lower

working piston 13 or when the parts are in the position as shown by Fig. 1.

When the pistons 13 and 14 are in the positions shown by Fig. 1, the charge of fuel or fuel mixture will have been fully compressed between the ends 15 and 16 of said pistons and an ignition will be immediately effected through the operation of the spark plug 25 by the usual timing mechanism, and when combustion ensues, the pistons are forced apart to effect the power stroke, as shown by Fig. 2. The piston 14 moves slower than the piston 13, the proportion as to time shown being one half, or, in other words, the piston 14 moves at one half the rate of speed of the piston 13. This timed operation is accomplished by securing on the lower crank shaft 9 a sprocket wheel 32 and applying to the upper crank shaft 10 a sprocket wheel 33 which is twice the diameter of the said lower sprocket wheel, these sprocket wheels being connected by a chain belt 34. For the purpose of practical illustration, the sprocket wheels 32 and 33 and the chain belt 34 are shown as the motion transmitting and timing means between the crank shafts 9 and 10, but it will be understood that any other suitable mechanical devices such as connected gearing might be used without in the least departing from the spirit of the invention. It will also be observed that the upper connecting rod 19 is attached to the crank 12 in closer relation to the upper crank shaft 10 than is the lower connecting rod 18 to its crank 11, and this difference in attachment of the connecting rods also affects and provides for the difference in time of movement of the two working pistons 13 and 14. When the pistons 13 and 14 have been driven apart by the explosion or combustion of the fuel or fuel mixture, the lower working piston 13 naturally depresses more rapidly within the cylinder and drives the crank shaft 9 at a greater rate of speed than the crank shaft 10 connected to the upper piston 14 which has a slower rising movement within the cylinder, and as the upper piston 14 rises, it elevates the compression piston 30 to clear the communication of the in-take pipe with the compression cylinder 6 and permit the latter to be charged, the upper piston 14 at this time being closed over the in-take port 27, as shown by Fig. 2, and the by-pass feature at such time also being clear or free of the combustion chamber or at an elevation above the said port 27. At this time also the lower combustion chamber port 28 is closed by the lower working piston 13 and such piston remains in this position, as illustrated by Fig. 3, owing to the fact that the lower crank 11 is turning in the regular arc of a circle relatively to the point of attachment of the connecting rod 18 with the lower piston 13 and until the

upper piston 14 clears the exhaust port 22 and permits the spent gases and products of combustion to pass outwardly through the said exhaust port into the exhaust pipe 23, 5 the upper working piston 14 being at the highest point of its stroke and the compression cylinder 6 below the compression piston 30 is fully cleared for a charge of fuel or fuel mixture below the compression 10 piston. When the lower crank 11 continues around as shown by the arrow in Fig. 3, until it reaches a little higher point than shown in said figure, the lower working piston 13 starts to move upwardly to force 15 the charge of spent gas and the remaining products of combustion fully from the combustion chamber 5^a so that the latter is thoroughly scavenged or cleaned prior to the admission of a new charge thereto. This 20 upward stroke of the lower working piston 13 continues until the lower crank 11 reaches the position shown by Fig. 4 and at such time the upper crank 12 will have passed the vertical center of its shaft 10 25 and moved to the right thereby causing the upper working piston 14 to descend and effecting a compression of the charge in the compression cylinder 6 beneath the compression piston 30, such compressing force 30 causing the check valve 21 to be forced into closed position and thereby relieving the in-take pipe 20 of back pressure. The compression of the charge in the compression cylinder 6 continues until the compression 35 piston 30 has its lower side in close adjacency to the upper end 31 of the cylinder 5 exposed within the said compression cylinder and at such time the upper working piston 14 will have descended to the lowest 40 limit of its stroke within the combustion chamber 5^a of the cylinder 5, closing the exhaust port 22 and bringing the by-pass structure of the cylinder into position to liberate the compressed charge by 45 opening the in-take port 27, the compression of the charge being effected for a certain interval downwardly through the by-pass and port and into the port 28. The lower working piston 13, however, will not have at such 50 time fully cleared the port 28 communicating with the combustion chamber 5^a, it being necessary for the lower crank 11 to descend below its shaft so that the connection for the rod 18 will be in vertical alinement with 55 said shaft, and when this position of parts ensues, the lower working piston will have cleared the said port 28 and permitted the preliminarily compressed charge to enter the combustion chamber between the two 60 pistons 13 and 14, the upper piston 14 during such operation of the lower piston 13 continuing to slowly move downwardly into the combustion chamber, and when it has reached its lowermost stroke will remain in 65 a maximum lowered position for an interval to serve as an abutment against which the lower working piston 13 after starting to move upwardly again within the combustion chamber will compress the charge until the lower piston again arrives at the position shown by Fig. 1 when explosion or combustion of the charge will be effected and the pistons again driven apart as hereinbefore explained. This cycle of operations will be effected regularly and it will 70 be seen that the preliminary compression of the charge of fuel or fuel mixture will be materially advantageous for the rapid supply of feed thereof between the two working pistons 13 and 14 when the lower port 75 28 is opened by the maximum descent of the lower working piston 13 and at such time it will be understood that the exhaust port 22 will be fully closed and will not be opened to clear the combustion chamber of the exploded charge until the working pistons 13 and 14 again assume the positions shown by Fig. 3. 80

In the modified form of the engine shown by Figs. 7 to 12, inclusive, the double working piston construction and the compression piston and relative parts are the same as in the first form described and similar reference characters have been applied to corresponding parts. In addition to the 85 features heretofore described, the modified form of the engine has a lower exhaust port 35 communicating with an exhaust pipe 36 and by this means the combustion chamber 5^a will be more quickly relieved of the spent 90 gases and products of combustion as the lower exhaust port 35 is opened to the combustion chamber 5^a simultaneously with the upper exhaust port 22. In the modified construction also the upper working piston 95 100 105 110 115 120 125 130 140

said lower working piston, the wear of this piston in the modified form of the construction being imposed on the sleeve valve. Moreover, the sleeve valve will more advantageously open and close the several ports and expose the spark plug, and, in turn, the lower working piston will control communication within the sleeve valve of the several ports of the latter relatively to 5 the combustion chamber which is defined by the said sleeve valve. The ignition of the successive charges and the explosion or combustion of the latter takes place in the modified construction in the sleeve valve 10 and thereby the cylinder is protected and will be rendered more durable and efficient. It is obvious that the piston with the sleeve valve may be more readily replaced than the cylinder in the event of deterioration 15 of the sleeve valve in part serving as the combustion chamber. It is also possible in the modified structure to form the cylinder of a lower grade of metal than the sleeve valve in view of the fact that the inner 20 wall of the cylinder is relieved of direct engagement and deterioration of the exploded gas and products of combustion.

The general operation of the several parts as shown in the modified construction 25 is the same as in the first form of the device with the exception of the double exhaust and indicating that one or more exhaust ports and pipes may be used, the object being to quickly liberate the spent gases 30 and products of combustion from the combustion chamber. Briefly referring to the operation of the modified construction, it will be seen from the position of the parts shown by Fig. 7 that the enlarged port or 35 opening 40 is opposite the sparking plug and exposes the latter to the compressed charge of fuel or fuel mixture between the pistons 13 and 14 when ignition is about to 40 take place. The two pistons as shown by 45 Fig. 8 have been affected by the explosion of the charge and have reached the end of their power stroke, the upper piston 14 continuing to slowly rise until the ports 39 and 40 register with the lower and upper 45 exhaust ports 35 and 22 while the lower piston 14 continues to descend to clear the lower port 39. During this exhaust the port 38 is elevated a distance from the port 28 and the latter port is closed by the sleeve 50 valve 37 and also the port 27 is closed by the upper piston 14, the compression cylinder 6 then receiving a charge of the fuel or fuel mixture through the intake 20, as in the first structure. In the position of the pistons as shown by Fig. 10, the exhaust has 55 been completed and the compression piston starts its descent with the upper working piston 14 and the lower piston 13 as closed, the lower port 39 is about to descend, while 60 the upper working piston 14 and sleeve valve 65

37 are gradually descending, the descent continuing until the port 38 registers with the port 28 to admit a charge between the pistons 13 and 14 for subsequent compression between the two pistons and ignition 70 and explosion as explained in connection with the position of the parts shown by Fig. 7.

Having fully described our invention, we claim— 75

1. In an engine of the class specified, an interiorly unobstructed single main cylinder having a compression cylinder at one end thereof, two oppositely disposed crank shafts respectively arranged near one end 80 of the main cylinder and the outer end of the compression cylinder, two pistons mounted in the cylinder and connected to the shafts and movable toward and from each other, one of the pistons having means fixed there- 85 to and movable therewith in the compression cylinder to compress the fuel toward the adjacent end of the main cylinder, and means for effecting a slower movement of one piston than the other. 90

2. In an engine of the class specified, an interiorly unobstructed single main cylinder having a compression cylinder at one end thereof provided with fuel supply means, two oppositely disposed crank shafts 95 coöordinated with the said cylinders, and ignition means mounted in and exposed through an intermediate portion of the main cylinder, and two pistons mounted to operate in the main cylinder at different speeds 100 and connected to the crank shafts, the slower moving one of the pistons having a compression piston fixed thereto and mounted to have the same timed movement in the compression cylinder to compress the fuel 105 toward one end of the main cylinder and into the latter.

3. In an engine of the class specified, a single main cylinder, two oppositely disposed crank shafts coöordinated with the 110 main cylinder, two pistons mounted in the cylinder and connected to the shafts and movable toward and from each other, the one piston having means fixed thereto and movable therewith for compressing the fuel 115 toward one end of the main cylinder, and means for effecting a movement of one piston one-half slower in time than the movement of the remaining piston.

4. In an engine of the class specified, a 120 main cylinder having a compression cylinder, the main cylinder having a by-pass in its side wall opening into the upper and lower extremities thereof to establish communication with the compression cylinder, 125 two crank shafts coöordinated with the cylinders, and ignition means mounted in and exposed through an intermediate portion of the main cylinder, and two pistons mounted in the main cylinder and connected to the 130

said shafts and one having a slower movement than the other, the slower moving piston operating to open and close the by-pass at intervals to alternately establish and cut off communication between the compression cylinder and the main cylinder, a compression piston being mounted in the compression cylinder and connected to the slower moving piston in the main cylinder and operating to compress the fuel toward and into the by-pass and between the pistons in the main cylinder.

5. In an engine of the class specified, an interiorly unobstructed main cylinder having a fuel by-pass with an interior opening adjacent to one end of the cylinder and extending downwardly through a part of the wall of the cylinder and also opening into the lower portion of the latter, the cylinder being further provided with exhaust means, two shafts coördinated with the cylinder, ignition means mounted in and exposed through an intermediate portion of the two oppositely working pistons mounted in the cylinder and connected to the shafts, the one piston controlling the opening and closing of the opening of the by-pass adjacent to one end of the cylinder and the remaining piston controlling the opening and closing of the remaining opening of the by-pass.

6. In an engine of the class specified, a main cylinder provided with a compression cylinder at one end and having a fuel supply inlet means, the main cylinder having a by-pass inlet means extending through a part of the wall of the same and opening into the upper and lower portions thereof, the main cylinder also being provided with an exhaust means, two shafts coördinated with the cylinders and two oppositely working pistons mounted in the main cylinder and connected to the shafts, the one piston moving slower than the remaining piston and controlling the opening and closing of the by-pass and having a compression piston connected thereto and movable in the compression cylinder to compress the fuel toward one end of the main cylinder, and ignition means mounted in and exposed through an intermediate portion of the main cylinder.

7. In an engine of the class specified, a main cylinder provided with a compression cylinder having a fuel inlet means, the main cylinder having a by-pass inlet extending through a part of the same and opening into the lower portion thereof, the main cylinder also being provided with exhaust means, two shafts coördinated with the cylinders, and two oppositely working pistons mounted in the main cylinder and connected to the shafts, the one piston moving slower than the other and controlling the opening and closing of the by-pass relatively to the

main cylinder and also having a compression piston connected thereto and moving in the compression cylinder.

8. In an engine of the class specified, a main cylinder provided with a compression cylinder having fuel inlet means, the main cylinder having a fuel by-pass inlet means extending through a part of the same and opening into the lower portion thereof and also having exhaust means, two shafts coördinated with the cylinders, and two oppositely working pistons mounted in the main cylinder and connected to the shafts, the one piston moving slower than the other and having a portion of the by-pass formed therein and controlling the opening and closing of the by-pass relatively to the main cylinder, the slower moving piston also having a compression piston connected thereto and moving in the compression cylinder.

9. In an engine of the class specified, a main cylinder inclosing a combustion chamber and having a compression cylinder on one end thereof, said compression cylinder being normally fully open to the main cylinder and provided with a fuel inlet, the main cylinder having a fuel by-pass with an inlet opening adjacent to the compression cylinder and an inner outlet opening at an intermediate portion of the said main cylinder, a lower crank case secured to the cylinder, crank shafts respectively extending into the crank case and over the compression cylinder, two pistons in the combustion chamber working in opposition and one slower than the other, the pistons being respectively connected to the crank shafts and one of the pistons having a compression piston in the compression cylinder, ignition means mounted in and exposed through the intermediate portion of the main cylinder to act between the opposing ends of the pistons in the combustion chamber, and connections between the crank shafts and the pistons.

10. In an engine of the class specified, a main cylinder embodying a combustion chamber and having a compression cylinder on the top thereof fully open into the said main cylinder and provided with a fuel supply inlet, the main cylinder adjacent to the combustion chamber having an inlet and a by-pass in the wall thereof, the by-pass having an outlet at the intermediate portion of the main cylinder, two crank shafts in opposition and disposed adjacent to the main and compression cylinders, two pistons with inner closed ends movable in opposite directions in the main cylinder and respectively connected to the crank shafts, one of the pistons having a compression piston movable in the compression chamber, the said compression piston and the piston to which it is attached controlling the inlet of the fuel to the compression chamber and

to the by-pass, ignition means disposed at an intermediate point in the combustion chamber, and means coöperating with the crank shafts for causing one piston to move 5 slower than the other.

11. In an engine of the class specified, a main cylinder having a compression cylinder, two oppositely disposed crank shafts disposed adjacent to the outer ends of the 10 main and compression cylinders, two pistons mounted and movable in opposite directions in the main cylinder and connected to the crank shafts and movable parts and to each other, the one piston having a compression 15 piston connected thereto and movable in the compression cylinder, the compression and main cylinders having fuel inlet means opened and closed respectively by the one piston in the main cylinder and the compression piston, the main cylinder also having exhaust means, intermediately positioned igniting means exposed through an intermediate portion of the main cylinder between the inner opposing ends of the two 20 pistons in said latter cylinder, crank shafts, and means coöperating with the crank shafts for causing the one piston having the compression piston connected thereto to move 25 slower than the other piston in the main 30 cylinder.
12. In an engine of the class specified, a main cylinder having a fuel by-pass extending through a part of the same and opening into the lower portion thereof, a compression cylinder on the main cylinder and having fuel inlet means, the compression cylinder also having communication at intervals with the main cylinder through the by-pass, the main cylinder being provided 35 with exhaust means, and an intermediately located ignition means, two shafts coöordinated with the main and compression cylinders and two oppositely working pistons mounted in the main cylinder and connected 40 to the shafts, the one piston also having a compression piston connected thereto and working in the compression cylinder and controlling the opening and closing of the fuel inlet to the compression cylinder, the 45 piston in the main cylinder having the compression piston connected thereto also controlling the opening and closing of the by-pass relatively to the main cylinder.
13. In an engine of the class specified, a 50 main cylinder having a compression cylinder with a fuel inlet, the main cylinder having a by-pass extending through a part of the same and provided with an inlet adjacent to the compression cylinder and an outlet into the 55 lower portion of the main cylinder, the main cylinder also being provided with exhaust and ignition means, two shafts coöordinated with the main and compression cylinders, and two oppositely working pistons mounted in the main cylinder and connected to the 60

shafts and one moving slower than the other, the slower moving piston having a compression piston working in the compression cylinder and the two latter pistons controlling the inlet of the fuel to the compression cylinder and the main cylinder. 70

14. An engine of the class specified comprising a cylinder having a fuel by-pass inlet communicating with opposite portions thereof and also provided with exhaust and ignition means, and reversely working pistons mounted in the cylinder and the one moving slower than the other, the slower moving piston controlling the inlet of fuel to the by-pass and the remaining piston controlling inlet of the fuel to the cylinder between the two pistons. 75

15. An engine of the class specified comprising a main cylinder having a fuel by-pass having two points of communication 80 with the cylinder, a compression cylinder coöperating with one end of the main cylinder and having a fuel inlet, the main cylinder also being provided with exhaust and ignition means, and two pistons working in opposition in the main cylinder and one moving slower than the other, the slower moving piston having a compression piston in the compression cylinder controlling inlet of fuel to the latter, and the said slower moving piston also controlling the one point of communication of the by-pass with the cylinder and the remaining working piston in the main cylinder controlling the other point of communication of the by-pass with the 85 main cylinder, the fuel being compressed into the by-pass by the compression piston prior to communication of the said by-pass with the interior of the main cylinder. 90

16. An engine of the class specified comprising a main cylinder having fuel inlet and exhaust means, ignition means mounted in and exposed through an intermediate portion of the said cylinder, and working pistons mounted within the said cylinder and moving in opposition to each other, the slower moving piston controlling the inlet of the fuel to the cylinder and the remaining piston controlling the inlet of fuel between the two pistons, and one slower than the 10 other, the inner opposing ends of the pistons being closed. 11

17. An engine of the class specified comprising a main cylinder having opposite open ends and provided with fuel inlet, exhaust and ignition means and also provided with means for preliminarily compressing the charge of fuel toward the one end of and forcing the compressed charge into the main cylinder, and two working pistons within the main cylinder having inner opposing compressing faces between which the preliminarily compressed charge is delivered and further compressed prior to ignition, the one piston moving slower than the other 12

but both connected for simultaneous operation, the ignition means being mounted in and exposed through an intermediate portion of the cylinders between the two working 5 pistons in the latter.

18. An engine of the class specified comprising a main cylinder having fuel inlet, exhaust and ignition means, two pistons mounted within the cylinder and working in 10 opposition to each other, the one piston being provided with a sleeve valve in which the other piston is mounted to move, the sleeve valve having ports for admitting the charge of fuel to the cylinder between the 15 pistons and for opening the exhaust means and exposing the ignition means, the one piston controlling the inlet of fuel to the main cylinder and the remaining piston controlling the inlet of fuel to the cylinder between 20 the two pistons.

19. An engine of the class specified comprising a main cylinder having fuel supply and fuel inlet exhaust and ignition means, and two working pistons mounted within 25 the cylinder and moving in opposition to each other, the one piston having a sleeve valve within which the other piston has movement, the piston carrying the sleeve valve having a slower movement than the 30 remaining piston and the sleeve valve formed with ports to permit entrance of the charge of fuel into the cylinder between the pistons, to open the exhaust means and to expose the ignition means, the piston with 35 the sleeve valve operating to control the inlet of the fuel through the sleeve valve from the fuel supply means of the main cylinder and the remaining piston working to control the inlet of fuel within the sleeve valve be- 40 tween the two pistons.

20. An engine of the class specified com-

prising a main cylinder with fuel inlet and upper and lower exhaust means and ignition means between the said exhaust ports, the main cylinder also having a compression 45 cylinder at one end normally open thereinto, and pistons working in opposition within the cylinder, the one piston having a sleeve valve within which the remaining piston is mounted and also having a compression piston 50 fixed thereto and movable in the compression cylinder, the sleeve valve being provided with ports to permit entrance of the fuel charge in the cylinder between the pistons, and to expose the upper and lower 55 exhaust means and the ignition means at proper intervals.

21. An engine of the class specified comprising a main cylinder having a full compression cylinder at one end and a fuel inlet 60 and upper and lower exhaust ports and ignition means between the said exhaust ports, and two main pistons working in opposition within the cylinder, the one piston having a compression piston connected thereto and 65 working in the compression cylinder and also provided with a sleeve valve within which the remaining main piston is mounted to operate, the sleeve valve being provided with ports to permit the entrance of the fuel 70 charge into the cylinder between the main pistons and to expose the exhaust ports and the ignition means at proper intervals.

In testimony whereof we have hereunto set our hands in presence of two subscribing 75 witnesses.
